UNITED STATES PATENT OFFICE.

HARRY SMOOKLER, OF LOS ANGELES, CALIFORNIA.

KITCHEN TOOL.

Application filed June 27, 1921. Serial No. 480,573.

To all whom it may concern:

Be it known that I, HARRY SMOOKLER, a citizen of the United States, residing at Los Angeles, in the county of Los Angeles and State of California, have invented new and useful Improvements in Kitchen Tools, of which the following is a specification.

My invention relates to a combination tool, particularly adapted for household use, the principal objects of my invention being to provide a relatively simple, strong and durable tool in which is combined a number of tools and devices that are frequently required for use about a household, and further to provide a convenient, compact combination tool that may be easily and cheaply produced.

With the foregoing and other objects in view, my invention consists in certain novel features of construction and arrangement of parts that will be hereinafter more fully described and claimed and illustrated in the accompanying drawings, in which:

Fig. 1 is a plan view of a combination tool of my improved construction with dotted lines showing parts of said tool in the positions they occupy when the tool is in use;

Fig. 2 is an edge view of the tool, and which view is taken looking in the direction indicated by the arrow 2 in Fig. 1;

Fig. 3 is an edge view of the tool, and which view is taken looking in the direction indicated by the arrow 3 in Fig. 1; and

Fig. 4 is a plan view of the forward end of the tool and showing parts thereof shifted into position to provide pinchers or nippers.

In the construction of my improved combination tool I make use of a pair of similar handles 10 and 11 each of which is preferably formed from a single piece of strip metal that is bent double to form parallel portions that are positioned immediately adjacent to each other and maintained in spaced relation by suitably located interposed plates 12, and the parallel portions of each handle are connected to each other by rivets or like fastening devices that are seated in said portions and in said spacing plates 12.

The parallel portions of each handle at the rear end thereof are spaced apart in order to form elongated openings, such as 13, and arranged in one of said openings 5 and pivotally connected to a pin or rivet,

such as 14, is a shank 15, the outer end of which is formed into a prong or puncturing member 16. This prong or puncturing member may be utilized for puncturing holes in thin sheet material, such as paper, metal, or leather, and while not in use the shank 15 occupies a position within the elongated opening in the handle to which it is connected.

Pivots connected to a pin or rivet 17 65 that is seated in the other handle is a cork-screw 18 which, when not in use, occupies a position within the opening 13 in the handle to which it is connected.

The inner edges of the parallel portions 70 of the handles are cut away at their forward ends to provide oppositely inclined faces 19, the same being transversely corrugated in order to form gripping faces 75 when the device is used as a pair of pliers or nippers, and the inner edges of the parallel portions of the handles to the rear of these inclined faces are transversely corrugated, as designated by 20, in order to form gripping edges when the tool is utilized 80 for engaging and screwing or unscrewing a relatively large object, such as a top for a preserving jar or can.

Positioned between the forward portions of the parallel members of handle 11 is 85 the rear end of a plate 21 with which is formed integral a forwardly projecting pointed blade 22 that may be utilized for opening thin sheet-metal cans, and formed integral with and projecting outwardly 90 from the rear portion of said plate 21 is a hook 23 that may be utilized for removing the metal closure caps of bottles.

Pivots connected to a pin or rivet 24 95 that is seated in the forward portion of handle 11 is one end of a curved arm 25 that extends between the parallel portions of handle 10, and formed in said curved arm is a row of apertures 26. Pivots mounted on a pin or rivet 27 that is seated 100 in the side of handle 10 near its forward end, is the rear end of an arm 28 that is provided at its forward end with a pair of oppositely arranged pins 29, either one of which is adapted to engage in one of the 105 apertures in curved arm 25. These pins 29 perform the functions of fulcrums for the handle 10 when the latter is swung toward or away from the handle 11 in performing certain operations with the tool, and there- 110

fore they serve for pivotally sustaining each of the handles or jaws irrespective of their relative positions.

Pivots mounted on pins 30 that are seated near the central portions of the handles 10 and 11, are the ends of links 31, the opposite ends thereof being pivotally connected to each other by a pin or rivet 31', said links forming a flexible connection between the intermediate portions of the handles, and spacing the handles apart from end to end, as indicated by dotted lines in Fig. 1.

By engaging one of the pins 29 in one of the apertures 26 of curved arm 25, the rear portions of the handles may be moved toward or away from each other so as to correspondingly move the forward portions of said handles toward or away from each other after the manner of the jaws of a pair of pliers or nippers, and the width or space between the forward portions of said arms, or the parts that serve as jaws, may be regulated by proper adjustment of the pins 29 in the apertures 26.

By proper adjustment and manipulation my improved combination tool may be utilized as a punch or puncturing device, a cork puller, a can opener, a bottle-cap remover, a nut cracker, as pliers or pinchers for engaging and handling various objects, for screwing or unscrewing the tops of preserving cans and the like, and by manually engaging the forward ends of the handles and spreading the rear ends apart, the tool may be utilized for handling relatively large objects, such as pieces of coal, briquets, and the like.

A combination tool of my improved construction is relatively simple, may be easily and cheaply produced, is very compact, and combines in a single structure a number of tools and devices that are generally useful about a household.

It will be understood that minor changes in size, form, and construction of the various parts of my improved combination tool may be made and substituted for those herein shown and described without departing from the spirit of my invention, the scope of which is set forth in the appended claims.

I claim as my invention:

1. In a combination tool, a pair of handles, links pivotally connecting the intermediate portions of said handles, a curved arm pivotally connected to the forward portion of one of said handles and extending

through the forward portion of the other handle, said curved arm being provided with apertures, and means on the handle through which said curved arm extends for engaging in one of the apertures in said curved arm to form a pivotal connection.

2. In a combination tool, a pair of handles, a curved arm pivotally connected to the forward end of one of said handles, said curved arm being provided with a row of perforations, means on the opposite handle for engaging any one of said perforations to form a pivotal connection, and the inner edges of the forward portions of said handles being corrugated.

3. In a combination tool, a pair of handles, a curved arm pivotally connected to the forward end of one of said handles, said curved arm being provided with a row of perforations, means on the opposite handle for engaging any one of said perforations to form a pivotal connection, the inner edges of the forward portions of said handles being corrugated, and pivotally connected links connecting the intermediate portions of said handles.

4. A tool comprising a pair of handles, an arm pivotally connected to one of the handles, means whereby one end of the other handle is adjustably connected to said arm, and links pivoted to each other and to the handles.

5. A tool comprising a pair of handles, an arm pivotally connected to one end of one handle, said arm being provided with a row of perforations, means on the other handle for engaging any one of said perforations to form a pivotal connection between the handles, and pivotally connected links connecting the intermediate portions of said handles.

6. A tool comprising jaws, a link connection between the jaws whereby the spaced position of the jaws from end to end can be varied, and means for pivotally sustaining each of the jaws irrespective of their relative positions.

7. A tool comprising jaws, a connection between the jaws whereby the spaced position of the jaws from end to end can be varied, and means for pivotally sustaining the jaws irrespective of their relative positions.

In testimony whereof I have signed my name to this specification.

HARRY SMOOKLER.
